UNITED STATES PATENT OFFICE.

ALBERT A. KEBL, OF BALTIMORE, MARYLAND, ASSIGNOR OF ONE-HALF TO JAMES J. PYCHA, OF BALTIMORE, MARYLAND.

LIFE-SAVING DEVICE.

1,296,967.

Specification of Letters Patent. Patented Mar. 11, 1919.

Application filed May 14, 1918. Serial No. 234,476.

To all whom it may concern:

Be it known that I, ALBERT A. KEBL, a citizen of the United States, residing at Baltimore, State of Maryland, have invented 5 certain new and useful Improvements in Life-Saving Devices, of which the following is a specification.

This invention relates to garments which are combined with a life preserver for suspending a person in the water, and its object 10 is to provide an inflatable, buoyant device which is so associated with the garment that the latter may be worn in the ordinary manner without discomfort, the buoyant device 15 being so constructed and arranged that it can be readily inflated.

The object stated is attained by means of a novel combination and arrangement of parts to be hereinafter described and 20 claimed, and in order that the same may be better understood, reference is had to the accompanying drawing forming a part of this specification, it being understood that while the preferred embodiment of the invention 25 has been illustrated, various changes and modifications in the structural details may be made without departure from the spirit and scope of the invention as claimed hereinafter.

30 In the drawing, Figure 1 is a perspective view of the garment spread open, and broken away in part to show the life preserver device associated therewith, and Fig. 2 is a sectional detail on the line 2—2 of Fig. 1.

35 Referring specifically to the drawing, the invention is shown applied to a sleeveless body garment similar to an ordinary vest, the same being constructed of any suitable material usually employed for garments of 40 this kind, and composed of an outer layer 5 with a lining 6 on the inner side thereof. The parts 5 and 6 are stitched together, or otherwise suitably united only at their edges so as to leave the space therebetween entirely 45 free and unobstructed. The garment may be provided with pockets as usual, and it is also provided with buttons or other suitable fasteners for holding it closed on the body of the wearer.

50 The life preserver device is composed of three inflatable bags denoted by the reference characters 7, 8 and 9, respectively. These bags are made of rubber or other suit-

able material, and they are positioned between the layers 5 and 6. One of the bags 55 is located at the back of the garment, and one is on each side, the side bags extending over as far as the front edges of the garment. The combined capacity of the bags, when inflated is therefore sufficient to sustain 60 the wearer in the water.

In order to prevent displacement of the bags 7, 8 and 9, each one has adjacent to the edge of the garment a flap 10 whereby it is fixed to the parts 5 and 6 by rows of stitches 65 11 passing through the latter and through the flaps.

Each side bag has an inflation tube leading to the upper edge portion of the garment and projecting a short distance therefrom so that the wearer may take the projecting end of either tube in his mouth for the purpose of blowing air through the same and into the bags for inflating the latter. These inflating tubes are shown at 12, and 75 where they join the bags they are each provided with a check valve 13 to prevent a return flow of the air.

Each side bag is connected by a tube 14 to the middle bag 8, these tubes being also 80 provided with check valves where they are joined to the middle bag, said valves being shown at 15. The middle bag is therefore inflatable from either one of the side bags 7 and 9, and for the purpose of deflating the 85 bags, the middle bag 8 is provided with a suitable deflator valve 16.

By providing the connections 14 between the bag 8 and the bags 7 and 9, and placing the check valves 15 in said connections, it 90 will be evident that in the event of puncture of either side bag, the middle bag will remain inflated, so that the wearer will be able to remain afloat with very little effort.

When the bags 7, 8 and 9 are deflated, they 95 lie flat between the parts 5 and 6, so that they do not add sufficient thickness to the garment to render the same uncomfortable to the wearer. The front and back linings of the garment are not sewed together as 100 usual, leaving the space between the parts 5 and 6 entirely free and unobstructed so that the bags may expand when they are inflated.

I claim:

The combination with a body garment 105 composed of inner and outer layers of mate-

rial which lap and are stitched together at their edges; of inflatable bags positioned between said layers and provided with inflating means, said bags having projecting flaps at the side seating between the lapping edge portions of the layers and secured therebetween by the stitching.

In testimony whereof I affix my signature in presence of two witnesses.

ALBERT A. KEEBL.

Witnesses:

E. WALTON BREWINGTON,
HOWARD D. ADAMS.
